UNITED STATES PATENT OFFICE.

ALONZO A. WARNER, OF NEW BRITAIN, CONNECTICUT, ASSIGNOR TO LANDERS, FRARY & CLARK, OF NEW BRITAIN, CONNECTICUT, A CORPORATION OF CONNECTICUT.

SAFETY-RAZOR.

1,207,247.

Specification of Letters Patent.

Patented Dec. 5, 1916.

Application filed April 13, 1916. Serial No. 90,800.

To all whom it may concern:

Be it known that I, ALONZO A. WARNER, a citizen of the United States, and a resident of New Britain, county of Hartford, State 5 of Connecticut, have invented certain new and useful Improvements in Safety-Razors, of which the following is a specification.

The object of this invention is to produce an article of the character described having 10 features of novelty and advantage.

In the drawings Figure 1 is a side view of a razor embodying my invention. Fig. 2 is a similar view but with the clamp plate raised. Fig. 3 is a rear view. Fig. 4 is a 15 sectional side view on the line 4—4 of Fig. 3.

Referring to the drawings, *a* denotes the handle, the upper end of which is bent slightly as at *b*, and has secured to it the base *c* provided at its front edge with a 20 guard *d* and at its rear edge with a longitudinal channel *e*. The upper end of the handle just underneath the base is slotted as at 2, and in this slot there is secured a spring 3 arranged underneath and longitudinally of the base, the spring comprising a pair of separate flat plates 5, 6, arranged side by side, the plane of the plates being at substantially right angles to the plane of the base, the rear spring plate 5 having at 25 its ends upstanding projections 7, 7, which are engaged by depending ears 8, 8, on the clamp plate 9, which fulcrums on the rear of the base and is connected to the base as by the lateral projections 10, 10, on the base 30 which extend into apertures 11 on the clamp. The blade 15 has a rib 16 secured at its rear end, which rib snugly fits into the channel *e* of the base, and thus holds the blade against shifting on the base.

It will be seen that the structure herein 40 illustrated and described is extremely simple, both for manufacture and use. The action of the ears 8 against the upstanding projections 7 of the spring plate 5, and the 45 use of the two separate spring plates provide a light and delicate spring action but of sufficient strength to firmly hold the blade in position on the base.

In accordance with the provisions of the 50 patent statutes I have described the principle of operation of my invention, together with the apparatus which I now consider to represent the best embodiment thereof; but I desire to have it understood that the

apparatus shown is only illustrative, and 55 that the invention can be carried out by other means.

I claim as my invention:—

1. In an article of the character described, a handle, a base secured to the end thereof, 60 a flat spring supported centrally in said handle and arranged underneath and extending longitudinally of said base, the plane of the spring being at substantially right angles to the plane of the base, and a 65 clamp plate having engagement with said spring and by it held in open or closed position.

2. In an article of the character described, a handle, a base secured to the end thereof, 70 a flat spring supported centrally in said handle and arranged underneath and extending longitudinally of said base, the plane of the spring being at substantially right angles to the plane of the base, and a clamp plate ful- 75 crumed on said base and having depending ears engaging the side of said spring.

3. In an article of the character described, a handle, a base secured to the end thereof, a flat spring supported centrally in said han- 80 dle and arranged underneath and extending longitudinally of said base, the plane of the spring being at substantially right angles to the plane of the base, and a clamp plate ful- 85 crumed on the base and provided at its ends with depending ears having angularly ar- 90 ranged faces engaging said spring in the open and closed position of said clamp plate.

4. In an article of the character described, a handle, a base secured to the end thereof, a 90 pair of spring plates arranged side by side supported centrally in said handle and ar- 95 ranged underneath and longitudinally of said base, the plane of said spring plates being at an angle to the plane of said base, and a clamp plate fulcrumed on said base 100 engaging one of said plates and acted upon by both of said plates.

5. In an article of the character described, a handle, a base secured to its end, a spring 100 plate centrally mounted in the handle and arranged underneath and longitudinally of the base, upstanding projections at the ends of said spring, a clamp plate fulcrumed on said base and engaging said upstanding pro- 105 jections.

ALONZO A. WARNER.
